UNITED STATES PATENT OFFICE.

JOHN O. E. KROHN, OF BARBERTON, OHIO, ASSIGNOR OF FORTY ONE-HUNDREDTHS TO INGOLF C. KLEPPE, OF CHICAGO, ILLINOIS.

ROTARY GAS-ENGINE.

No. 839,300.

Specification of Letters Patent.

Patented Dec. 25, 1906.

Application filed May 15, 1905. Serial No. 260,455.

To all whom it may concern:

Be it known that I, JOHN O. E. KROHN, a citizen of the United States, and a resident of Barberton, in the county of Summit and State of Ohio, have invented certain new and useful Improvements in Rotary Gas-Engines, of which the following is a full, clear, and exact description.

The object of my invention is to provide a gas-engine in which the cylinders revolve around an axis arranged at an angle to the axis of the drive-shaft actuated thereby and are kept comparatively cool by the circulation of air caused by their rapid rotation. This I accomplish by the means hereinafter fully described, and as particularly pointed out in the claims.

In the drawings, Figure 1 is a side elevation of my improved gas-engine. Fig. 2 is a vertical central section of the same. Fig. 3 is a horizontal section thereof, taken on dotted line 3 3 of Fig. 2 looking in the direction indicated by the arrows. Fig. 4 is a diagrammatical view disclosing the construction and operation of the valve-controlled inlet and outlet parts of the cylinders and mechanism for actuating the same. Fig. 5 is a plan view.

Referring to the drawings, A represents a suitable drive-shaft, which is provided with bearings A² and A³, forming part of and preferably cast in one piece with a suitable circular base B. These bearings A² and A³ are preferably located to one side of the base B and so that the axis of the shaft A, journaled therein, will intersect the vertical axis of said base. The shaft A is stepped to a greater diameter between its said bearings than it is in bearings A² and preferably is stepped to a still greater diameter in the bearings A³ and terminates in a truncated cone-shaped extension A' in the well or trough B' in the bottom of the base B. The end portion of the shaft A, terminating within the base B, is provided with a longitudinal central bore or socket a, and seated in this socket is the horizontal portion of an L-shaped bracket C, the angle or bend of which is just beyond the extremity of the shaft A and the axis of the vertical arms of which is substantially at right angles to its horizontal portion and alines with the vertical axis of the base B.

At a point just above the bend of the bracket C the latter is slightly reduced in

diameter to provide a supporting-shoulder 55 for a suitable ball-bearing cup c, which is brazed or otherwise suitably secured to the said arm. The annular chamber of this cup, in which the balls c travel, is located between the circumference of the vertical arm of the bracket C and the outer circumference of said cup c and supports a suitable ball-bearing cap or cover d, which latter is secured to the lower end of the central boss e of the circular spider-frame E. This spider-frame E 65 is provided with a series of equidistant radiating arms preferably corresponding in number to the number of cylinders possessed by my invention, as will hereinafter more fully appear. Mediate the center of revolution of this spider-frame and the outer circular rim said arms are provided with guide-bearings e' for the pistons of the cylinders, hereinafter referred to, and the outer circumference of the said rim at the lower end of 75 this cylindrical portion is provided with a shoulder e², in which is seated a suitable bearing-ring F, which latter is substantially angle-shaped in section and has bearing-balls f seated therein that engage the under side of 80 the cover G for the base B between the outer circumference of the upper cylindrical portion of the rim of the spider-frame and the side of said base.

Secured to the vertical arm of the bracket 85 C above the boss e of the spider-frame is a stationary pinion g, and surrounding the upper end of this arm above this pinion is a hub or boss h, having a series of arms radiating therefrom that connect it with the rim of 90 the spider-frame in suitable manner and correspond in position and number to the arms of said spider-frame. These radiating arms of boss h are provided mediate their ends with guide-openings through which the pistons operate, and between these guide-openings and guide-bearings e' in the arms of the spider-frame E a gear H is loosely journaled, which supports and has an annular cam I secured to its rim, to which more extended 95 reference will be had hereinafter. Suitably secured at their lower ends to the cover G, between the rim of the spider-frame and the hub or boss h thereof, is a series of corresponding cylinders, the vertically-disposed 100 axes of which incline outward from the lower to the upper end thereof and are placed the same distance from the axis of the vertical

portion of the arm C, or, in other words, the center of revolution of the spider-frame E. The upper portion of these cylinders is provided with a series of circumferential flanges 5 j, and the upper end or head of the same is provided with a series of vertical ribs j', which greatly increase the condensing - surface of the cylinder and as the cylinders revolve around the axis of the bracket C greatly 10 assist in cooling the cylinders by reason of the circulation of air caused by their movement. These cylinders each have a piston-rod J and a piston-head K, which latter has the upper end of the piston-rod so secured 15 therein that it can revolve and has a rotation of its own independent of the head and cylinders. These piston-rods J are all of the same length and have their lower ends provided with angular extensions J' at substantially 20 right angles to their upright portions, that are journaled in an annulus k, surrounding but unconnected with the bend of the bracket C and placed at an angle or in an inclined plane striking through the center of 25 length of said bend, substantially at right angles to the axis of the center of said bend, adjacent to the extremity of the shaft A, within the base B and the well B' thereof. The end of shaft A extending into the base is 30 provided with a series of equidistant longitudinally-disposed holes m therein, which extend in an inclined direction from their mouths (located between the center of the end of the shaft and the circumference thereof) to a point nearer the center of revolution, just beyond their bearings in the base. Entering and having reciprocating play in these 35 openings or sockets m are plungers M, the outer ends of which are made integral with 40 the extensions J' of the piston-rods J.

The cylinders, as has been explained, revolve around the axis of the vertical arm of bracket C, and when the pistons are at the limit of their upward stroke the cylinders 45 thereof will be directly above the extremity of shaft A, in which position the bearings of the angular extension of the piston in the annulus k will be at the highest point reached by it during its cycle of motion around the 50 bend of arm C. The pistons will arrive at the limit of their downward stroke when the cylinders have revolved in a position diametrically opposite the position they occupy when the piston is at the limit of its upper 55 stroke, and then the bearings in the annulus k of the angular extension of the piston will be at the lowest point of the cycle of movement described thereby during the rotation of said annulus k. The revolution of the cylinders and the reciprocating movement of the piston therein imparts to the annulus k a 60 revolution around the bend of the arm C, and its rotary movement is imparted, through the medium of plungers M, to the shaft A by 65 virtue of their engagement with the holes or

sockets m therein, in which as said shaft A revolves they slide back and forth or reciprocate.

The cam I has a hump or raised portion i at a given point on its upper face, and this 70 cam revolves but once during every two revolutions of the cylinders around the vertical arm of bracket C by reason of the gear H having twice as many teeth as the stationary pinion on the bracket C, which it engages. 75 This cam is engaged by a friction-roller q, journaled between the cross-bars of a frame Q, the parallel legs of which extend past and embrace the piston to which said cam is concentric and have their extremities suitably 80 connected. The end of this frame farthest from the piston has a slight extension, and this extension is engaged by a vertical rod R, the upper end of which engages a U-shaped link r. The legs of this link extend vertically 85 upward on either side of the inlet and exhaust pipes S and T, respectively, and have their upper extremities connected to the widened end of lever 2. These levers are preferably arranged radially to the center of 90 revolution of the cylinders and are journaled in lugs s s, projecting from the top of the valve-chamber 3, with the lower end of which the upper extremity of the inlet-pipe S is connected and with the upper end of 95 which the outer end of the exhaust-pipe T is suitably connected. The rod R is kept normally pressing downward and retains the friction-roller Q on the cam I by means of a coil-spring N, interposed between the lower 100 bend of the link r and the under side of the inlet-pipe, substantially as shown in the drawings.

The body of valve-chamber 3 is preferably cylindrical, and the upper portion of its interior chamber, with which the exhaust-pipe T connects, and the lower portion of said interior chamber, with which the inlet-pipe S connects, are separated from the central portion by means of valve-seats 4 5, respectively, to form a union-chamber 6, with which the upper end of the cylinder on one side thereof connects by means of a nipple 7. A blind or solid nipple connects the opposite side of the said union-chamber to the cylinder on the other side thereof. The upper valve-seat 4, through which communication between the union-chamber and the exhaust-pipe T is established, is alternately opened and closed by a valve 8, which bears against the valve-seat on the side of the union-chamber. This valve 8 has a spindle arising vertically therefrom, which extends up through suitable guide-bearings in the top of the valve-chamber and is pivotally connected to the adjacent end of the lever 2, which latter causes the valve to open every time the link r is raised by the action of the rods R. The lower valve-seat, through 115 which communication between the inlet-pipe 120

and the union-chamber 6 is established, is normally closed by an inlet-valve 9, bearing against the side of the valve-seat next the union-chamber, and is provided with a spindle which extends through suitable guide-bearings in the lower end of the valve-chamber 3, preferably in alignment with the axis of the valve 8, and has the lower end thereof extending below its bearings surrounded by a coil expansion-spring 10 between the nut on the lower end thereof and the bottom of the valve-chamber, that normally retains said valve in a position to close said valve-seat. When the piston-head K in the cylinders is at the limit of its upward stroke and the spent gases therein are to a great extent exhausted out through the nipple 7, the union-chamber 3, and the exhaust-pipe T, and when it commences its downward stroke, the exhaust-valve 8 closes and a suction is created which automatically opens the inlet-valve 9 and draws into the upper end of the cylinder a sufficient quantity of carbureted air or gas, which is ignited by a sparkler 11 of the usual construction, located in the upper end of the cylinder, as shown. When the piston-heads K have reached the limit of their downward movement, the raised portion i of the cam I will engage the friction-roller q, and the frame Q, in which the latter is journaled, will move the rod R and the link r longitudinally and rock lever 2, and thereby open the exhaust-valve 8 to permit of the exhaust of the spent gases in the cylinder during the upper or return stroke of the piston-head through the nipple 7, the union-chamber 6, and the exhaust-pipe T. There are preferably four of these exhaust and inlet pipes and conjunctive mechanism used in connection therewith which are, when four cylinders are used, so arranged that one exhaust-pipe and one inlet-pipe extend radially from the center of revolution centrally between each two cylinders. The inner ends of the inlet-pipes S converge toward and have their upturned inner ends merge into and communicate with a hollow central journal 12, the upper end of which has bearings in a stationary head 14 and is provided with a suitable nut 13, that closes its upper end. The bearings in the upper portion of this head 14 provided with an annular passage 15, with which the upper end of the bore of said journal 12 communicates at all times through a circumferentially-arranged series of inlet-ports 16, whereby the carbureted air or gas, which is continuously fed into the annular passage 15 by a suitable supply-pipe 17, can enter the bore of journal 12 and from thence into the inlet-pipes S. The inner ends of the exhaust-pipes converge toward and communicate with an integral hub 18, which surrounds and is concentric with the hollow journal 12 and has bearings in the lower portion of the head 14, substantially as shown.

This hub is provided with vertical passages that form extensions 19 of the bore of the exhaust-pipe T, the upper ends of which communicate with an annular passage 20 in the head 14 by means of suitable openings in the hub, and this annular passage 20 discharges the exhaust-gases out through a suitable exit-pipe 21, leading from said head 14, substantially as shown.

What I claim as new is—

1. A gas-engine comprising a driven shaft, a series of cylinders arranged and bodily revolving around an axis extending at substantially right angles to that of said shaft, and piston-rods for said cylinders, which reciprocate longitudinally in said shaft. 75

2. A gas-engine comprising a driven shaft, a series of cylinders arranged and bodily revolving around an axis extending at substantially right angles to that of said shaft, a ring 85 or annulus placed between and inclined at an angle midway that of said axes, piston-rods reciprocating in said cylinders which are suitably connected to said annulus, and reciprocate longitudinally in said shaft.

3. A gas-engine comprising a driven shaft, a series of cylinders arranged and bodily revolving around an axis extending at an angle to that of said shaft, a ring or annulus placed between and inclined at an angle midway 95 that of said axes, pistons reciprocating in said cylinders the outer ends of which are suitably connected to said annulus, and plungers operatively connected with said annulus reciprocate longitudinally in said shaft. 100

4. A gas-engine comprising a driven shaft, a series of cylinders arranged and bodily revolving around an axis extending at an angle to that of said shaft, a substantially L-shaped bracket the legs of which are respectively 105 parallel with the axes of said shaft and said series of cylinders, and pistons for said cylinders which are operatively connected to said shaft.

5. A gas-engine comprising a driven shaft, 110 a series of cylinders arranged and bodily revolving around an axis extending at an angle to that of said shaft, a substantially L-shaped bracket the legs of which are coincident with the axes of and connect said shaft and the axial support of said cylinders, a ring or annulus placed between and inclined at an angle midway that of said axes, pistons reciprocating in said cylinders the outer ends of which are suitably connected to said annulus, 115 and means for imparting the motion of said annulus to said shaft. 120

6. A gas-engine comprising a driven shaft, 125 a series of cylinders arranged and bodily revolving around an axis extending at an angle to that of said shaft, a substantially L-shaped bracket, the legs of which are coincident with the axes of and connect said shaft and the axial support of said cylinders, a ring or annulus placed between and inclined at an an-

gle midway that of said axes, pistons reciprocating in said cylinders the piston-rods of which are suitably connected to said annulus, and plungers operatively connected with said annulus and reciprocating longitudinally in said shaft.

7. A gas-engine comprising a driven shaft, a series of cylinders arranged and bodily revolving around an axis extending at substantially right angles to that of said shaft, a revolving support for said cylinders, valve-controlled inlet and exhaust pipes for said cylinders which converge toward and form the upper journaling devices for said cylinders, and piston-rods for said cylinders, which reciprocate longitudinally in said shaft.

8. A gas-engine comprising a driven shaft, a series of cylinders arranged and bodily revolving around an axis extending at substantially right angles to that of said shaft, a revolving support for said cylinders, a super-

imposed head the axis of which alines with the center of revolution of said support, valve-controlled inlet and exhaust pipes for said cylinders which converge toward and form a journal having bearings in said head, and piston-rods for said cylinders which reciprocate longitudinally in said shaft.

9. A gas-engine comprising a driven shaft, a series of cylinders each having a separate valve-controlled gas inlet and exhaust devices, and arranged and bodily revolving around an axis extending at substantially right angles to that of said shaft, and piston-rods for said cylinders which reciprocate longitudinally in said shaft.

In testimony whereof I have hereunto set my hand this 3d day of March, A. D. 1905.

JOHN O. E. KROHN.
